UNITED STATES PATENT OFFICE.

MAURISE KRANTZ, OF LONDON, ENGLAND.

BAG OR RECEPTACLE FOR STORING AND PRESERVING FURS, ARTICLES OF WEARING APPAREL OR THE LIKE.

Application filed May 9, 1925, Serial No. 29,197, and in Great Britain June 17, 1924.

This invention relates to an improved bag or receptacle for storing and preserving furs, articles of wearing apparel or the like, and it has for its object to provide an improved bag 5 or container in which articles may be stored or protected from moths or other insects, damp or injurious climatic conditions.

A bag or receptacle according to this invention comprises a body formed of flexible 10 waterproof and airproof material.

I am aware that bags for holding mail have been proposed in which the mouth of the bag has been provided with rigid bodies hinged together and adapted to more or less 15 form a square when the bag is opened, screws or other means being provided whereby the strips may be clamped together when the bag is closed.

I am further aware that in order to secure 20 an airtight closure at the mouth of a bag for mail or other purposes, it has been proposed to employ metal frames, one of which is channelled to contain a strip of rubber which, when the bag is closed, is pressed 25 against the other frame to seal the bag.

According to the present invention there is provided on the faces of the strips, rubber 20 or other elastic material by which when the bag is closed a continuous rubber to rubber 25 or like contact is secured around the mouth of the bag, forming an airtight and damp-proof joint.

The strips may be drawn together in the known manner by means of thumb screws, 35 clips or other suitable devices. Provision is made within the bag for hanging the articles, a hook or other device being provided upon the exterior of the bag for hanging in a wardrobe or other place.

40 In order that the invention may be the better understood, drawings are appended in which:—

Fig. 1 is an elevation of a bag according to this invention;

45 Fig. 2 is a plan showing the upper end of the bag closed;

Fig. 3 is a vertical section on line AA, Fig. 1;

50 Fig. 4 is a vertical section on line BB, Fig. 2.

Referring to the accompanying drawings, a indicates the bag which may be made of india rubber, rubberproofed fabric, oiled silk or other material impervious to air and moisture.

Secured in any suitable manner, to the mouth of the bag are four strips or lengths of rigid material b, which strips are preferably formed of metal and are hinged together as shown, so that they may either be 60 extended, as shown by the dotted lines in Fig. 2, to allow of ready access to the bag, or disposed in pairs parallel to each other to close the bag as shown in full lines in the said figure.

The strips are applied outside the material and when the bag is closed the strips of each pair are pressed tightly together by means of the thumbscrews c, the material of which the bag is formed, which in the example illustrated is assumed to be india-rubber, being 70 sufficiently resilient to form an air-tight joint.

Alternatively where the material employed is not of a resilient nature a pad or cushion of rubber or the like, is provided upon the 75 contacting surfaces of rigid members at the mouth of the bag.

The furs, garments or the like are supported within the bag in any suitable manner. Thus for example a hook d may be provided 80 from which a clothes hanger or the like may be suspended.

Preferably, in order to secure immunity 85 from insect pests, a suitable insecticide may be placed in the bag.

What I claim is:

A bag for storing and preserving furs, articles of wearing apparel and the like, comprising in combination a flexible, damp and air-proof rubber body material having an opening, four hingedly connected flat strips of rigid material of substantially the same length and applied to the said opening against the border of the air proof rubber body material itself, means for pressing the 90 four flat strips in such a manner that two of the strips are in line with each other and are pressed with one half of the border of the rubber air-proof body material against the two other strips lined with the other half of the border of the rubber air-proof body material and which are also in line with each other and so that two hinges covered with the rubber like material come opposite each other thus forming a continuous rubber to 95 rubber contact, extending also to the hinges, with the air-proof body material itself.

Signed in London, England, this 20th day of April, 1925.

MAURISE KRANTZ.
